(57) **CLAIM**

The ornamental design for a planter, as shown and described.

DESCRIPTION

FIG. 1 is a front elevation view of a first embodiment of a planter showing my new design;

FIG. 2 is a top plan view of FIG. 1;

FIG. 3 is a left side elevation view of FIG. 1;

FIG. 4 is a right side elevation view of FIG. 1;

FIG. 5 is a rear elevation view of FIG. 1;

FIG. 6 is a bottom view of FIG. 1;

FIG. 7 is a front, top and right side perspective view of FIG. 1;

FIG. 8 is a front, bottom and right side perspective view of FIG. 1;

FIG. 9 is a right side section view taken along the section line in FIG. 1;

FIG. 10 is a front elevation view of a second embodiment of a planter;

FIG. 11 is a top plan view of FIG. 10;

FIG. 12 is a left side elevation view of FIG. 10;

FIG. 13 is a right side elevation view of FIG. 10;

FIG. 14 is a rear elevation view of FIG. 10;

FIG. 15 is a bottom view of the planter of FIG. 10;

FIG. 16 is a front, top and right side perspective view of FIG. 10; and,

FIG. 17 is a front, bottom and right side perspective view of FIG. 10.

The broken lines shown in the figures depict portions of the planter that form no part of the claimed design.

1 Claim, 17 Drawing Sheets
